Primary Examiner—Raphael Barkai*Attorney, Agent, or Firm*—Katherine McGuire[57] **CLAIM**

The ornamental design for eyewear, as shown and described.

DESCRIPTION

FIG. 1 is a front perspective view of eyewear showing my new design;
 FIG. 2 is a front elevational view thereof;
 FIG. 3 is a side elevational view thereof;
 FIG. 4 is a top plan view thereof;
 FIG. 5 is a bottom plan view thereof;
 FIG. 6 is a front perspective view of eyewear showing a second embodiment of my new design;
 FIG. 7 is a front elevational view thereof;
 FIG. 8 is a side elevational view thereof;
 FIG. 9 is a top plan view thereof;
 FIG. 10 is a bottom plan view thereof;
 FIG. 11 is a front perspective view of eyewear showing a third embodiment of my new design;
 FIG. 12 is a front elevational view thereof;
 FIG. 13 is a side elevational view thereof;
 FIG. 14 is a top plan view thereof; and,
 FIG. 15 is a bottom plan view thereof.
